UNITED STATES PATENT OFFICE

FRANK KILBERG, OF DETROIT, MICHIGAN

WEATHER STRIP

Application filed June 7, 1929. Serial No. 369,024.

The present invention pertains to a novel weatherstrip designed especially for use in windows of the sliding sash type.

The principal object of the invention is to provide a construction of this character which not only serves as a weatherstrip, but also as a means for holding the sash in elevated position, so that sash weights are not necessary. Moreover, the weatherstrip is constructed in such a manner that a single unit made of one piece of metal is adapted to serve two sashes, thus affording a substantial improvement over the device shown in my co-pending application, Serial No. 321,860, filed November 26, 1928.

The device consists essentially of a strip of sheet metal having a central channel which fits into the parting strip groove between the two sashes, and is provided with wings which extend into the ways for the sashes. The wings are made resilient with respect to the channels by any suitable means which will tend to move them against the longitudinal edges of the sashes. The resiliency may be provided by doubling the metal at the bend between each wing and the channel, or in lighter constructions the wing need not be entirely doubled but merely formed with a spring piece which engages the bottom of the way for the sash.

Each wing bears against the adjacent edge of the sash and forms a weather seal, and also springs into the frame opening to support the sash in an elevated position.

The invention is fully disclosed by way of example in the following description and in the accompanying drawing, in which—

Figure 1 is a fragmentary horizontal section of a window construction showing the improved weatherstrip in section;

Fig. 2 is an end view of a modified strip;

Fig. 3 is a horizontal section of a window equipped with a lighter form of weatherstrip;

Fig. 4 is a perspective view of the weatherstrip shown in Figure 3; and

Fig. 5 is an end view of another modification.

Reference to these views will now be made by use of like characters which are employed

to designate corresponding parts throughout.

In Figure 1 is illustrated a side 1 of a window frame having three parallel channels 2, 3 and 4 formed therein. The channels 2 and 4 contain moldings 5 and 6 respectively, and the intermediate channel 3 is adapted to receive a parting strip 7 which projects into the window opening. In this manner the window frame is divided into two adjacent ways 8 and 9, the former being located between the strips 5 and 6 and the latter between the strips 7 and 6.

The weatherstrip constituting the subject matter of this invention is a sheet metal member formed with a central channel 10 fitted into the channel 3 and in turn receiving the parting strip 7. From the edges of the channel, wings 11 extend outwardly across the bottoms of the ways 8 and 9 and are then bent back upon themselves to form plies 12 beneath the parts 11. The two-ply formation is also carried out at the bend 13 between each wing and the corresponding lateral wall of the channel and along said lateral walls as indicated by the numeral 14 in Figure 1. Each wing is sprung outward into the corresponding way by making the angle at the bend 13 greater than a right angle. The tendency of the wings to take the position shown at the righthand side of Figure 1 is increased by the two-ply character of the metal at the bends 13. The wings tend to assume this position wherever they are not engaged by a sash. Consequently, when a sash is raised, the metal exerts a pressure on the vertical edges thereof and holds the sash in its elevated position, so that sash weights are not necessary.

The outer edges of the wings are bent to form lips 16 which come into firm engagement with the adjacent parting strips wherever the wing is brought towards the bottom of the way by the sash, and in such position the lips further improve the seal by preventing flow of air around the parting strips.

These lips may however be dispensed with as shown in Figure 2 which also illustrates that the tension of the wings 20 may be in-

creased by forming longitudinal corrugations 21 therein adjacent the bends 22.

In Figures 3 and 4 is illustrated another modification wherein the lower lap 25 of each wing is not extended as far as the bend 26. This construction is suitable for lighter windows wherein the tension at the single bend 26 in addition to the spring action of the lap 25 is sufficient for the purpose of sustaining the sash in the manner described.

Still another modification of a light construction is shown in Figure 5. In this case the lower lap 27 of each wing is still shorter, but is concave at the side facing the main lap or wing 28. It will be obvious that in this case the member 27 acts as a spring tending to move the wing 28 into the way for the sash. Lips 29 may be provided at the outer ends of the wings but are optional in any one of the constructions illustrated.

Although specific embodiments of the invention have been illustrated and described, it will be understood that various alterations in the details of construction may be made without departing from the scope of the invention, as indicated by the appended claims.

What I claim is:—

1. A weatherstrip comprising a channel adapted for insertion in the parting strip groove of a window frame, wings extending outwardly from the edges of said channel and adapted to lie in the sash ways of a window frame, and resilient means tending to hold said wings in a position non-perpendicular to the sides of said channel.
2. A weatherstrip comprising a channel adapted for insertion in the parting strip groove of a window frame, wings extending outwardly from the edges of said channel and adapted to lie in the sash ways of a window frame, and lips formed on the free edges of said wings.
3. A weatherstrip comprising a metal channel adapted for insertion in the parting strip groove of a window frame, and integral wings extending outwardly from the edges of said channel and adapted to lie in the sash ways of a window frame, the metal constituting said channel and wings being doubled at the bend between each wing and the adjacent side of said channel.
4. A weatherstrip comprising a metal channel adapted for insertion in the parting strip groove of a window frame, and integral wings extending outwardly from the edges of said channel and adapted to lie in the sash ways of a window frame, each wing being grooved longitudinally adjacent the bend between the wing and the adjacent side of the channel.

In testimony whereof I affix my signature.
FRANK KILBERG.
